(57) **CLAIM**

The ornamental design for a laptop stand as shown and described.

DESCRIPTION

FIG. 1 is a top, right and rear perspective view of a laptop stand showing my new design;

FIG. 2 is a bottom, left and front perspective view

FIG. 3 is front view thereof;

FIG. 4 is back view thereof;

FIG. 5 is a left-side view thereof;

FIG. 6 is a right-side view thereof;

FIG. 7 is a top view thereof;

FIG. 8 is a bottom view thereof; and,

FIG. 9 is an enlarged view of an encircled portion 9 of FIG. 2.

The dash-dash broken lines in the drawings depict portions of the laptop stand that form no part of the claimed design. The dot-dash broken lines illustrate the boundaries of the enlarged detail view and form no part of the claimed design.

1 Claim, 9 Drawing Sheets
